DESIGN FOR A REVERSIBLE EMBROIDERED COLLAR OR SIMILAR ARTICLE

Harry Bonn, Union City, N. J.

Application November 9, 1939, Serial No. 88,131

Term of patent 3½ years

To all whom it may concern:

Be it known that I, Harry Bonn, a citizen of the United States of America, residing in Union City, county of Hudson, and State of New Jersey, have invented a new, original, and ornamental Design for a Reversible Embroidered Collar or Similar Article, of which the following is a specification, reference being had to the accompanying drawing, forming part thereof, wherein:

I claim:

The ornamental design for a reversible embroidered collar or similar article, substantially as shown.

HARRY BONN.
